STABILIZATION OF OILS

Sidney Musher, New York, N. Y., assignor to
 Musher Foundation Incorporated, New York,
 N. Y., a corporation of New York

No Drawing. Application July 18, 1940,
 Serial No. 346,145

9 Claims. (Cl. 260—398.5)

The present invention relates to the stabilization of glyceride oils and particularly to the stabilization against oxidative deterioration of those glyceride oils which contain a large proportion of unsaturated glycerides.

It has been found that these oils are particularly oxidizable and that this deterioration is increased wherever the oils are subjected to high temperature deodorization during the refining process.

It has now been found that when such glyceride oils are heated to relatively high temperatures with finely divided de-oiled spice residues, instead of losing stability and becoming more subject to deterioration, the oils will become very stable and highly resistant to oxidative deterioration and rancidity.

The spice residues, and particularly clove and cinnamon residues, in finely divided and substantially oil exhausted form, are dispersed in the glyceride oil which is then heated or they may be added to the oil during high heat treatment to develop marked antioxygenic effectiveness.

For example, the essential and fixed oils may be substantially removed from the spices by steam distillation, expression or extraction and the residue thus obtained, preferably finely divided to about 50 mesh and desirably to over 100 mesh, may be added to the oil and heated therein.

The spice residue is added in an amount of less than 10% and desirably less than 2%. As little as 0.05% to 0.5% will give highly desirable stabilizing results when the glyceride oils are treated in accordance with this invention.

After dispersing the spice residue in the oil, the oil is heated to an elevated temperature, desirably in excess of 250° F. and preferably to between 325° F. and 450° F. for at least 15 to 30 seconds.

It has been found that merely melting a glyceride fat or oil, particularly where the glyceride is solid at room temperature, is not sufficient to give the desired effect and it is necessary to utilize an elevated temperature substantially above the melting point of the glyceride if it normally be solid at room temperature.

During the heating period, the residue may become burnt or charred and, where desired, the burnt residue may be removed as by filtration or centrifuging from the body of the oil, as the stabilization of the oil will already have been effected.

This charring apparently enhances the action of the spice residue on the oil and it has been found particularly desirable for the heating to be

sufficiently high so as to produce charring in order to obtain the fully desirable results of the present invention.

The oil which has been heated with the spice residue will be darker as the result of the elevated temperature treatment and the stabilization will have been effected even though the charred residue be removed from the oil as by filtration or centrifuging.

10 It, however, has been found that the original light color of the oil may be restored by a bleaching process as, for example, with fuller's earth or other decolorizing materials and still retaining a substantial enhancement in the stability of the oil.

15 The results of the present invention are particularly surprising since antioxidants are recognized as losing at least a portion of, and in most cases a major portion of their effectiveness when heated to elevated temperatures such as to 400° F. or more.

Example I

Bleached refined lard was treated by adding thereto and mixing therein 0.5% of clove residue, 25 which had been finely divided to about 50 mesh. The lard containing the residue was then heated to 400° F. for 30 seconds, allowed to cool, and filtered to remove the charred clove residue solids. The lard was thereupon tested by bubbling air 30 through a 20 cc. sample of the lard at 125° F. until rancidity as determined organoleptically and by peroxide values was observed. A sample of lard from the same lot to which 0.5% of clove residue was added but without being subjected to the 400° F. heat treatment was similarly tested along with a sample of the original untreated lard, with the following results.

		Rancid after—
40	Untreated lard	2 hours
	Lard containing 0.5% clove residue unheated	3½ hours
	Lard containing 0.5% clove residue heated to 400° F. for 30 seconds, cooled and filtered	14 hours

45 The glyceride may, where desired, be bleached or otherwise refined after treatment at the elevated temperature with the spice residue and a distinct enhancement of the antioxygenic effect will be obtained, such enhancement being far in excess of normal expectation.

50 It is not desirable for the heating to be conducted in a small body of the oil and that oil used as a base for addition to a large body of oil. The most desirable method is for the spice

residue to be dispersed in the entire body of material to be stabilized, followed by subjecting the oil to a high heat in order to produce the desired interaction or result.

Apparently a chemical reaction occurs between certain components of the spice residue which may be placed into reactive condition by the de-oiling of the spice residue and the oil at the elevated temperature whereby the stabilization is effected, as this reaction does not appear to be related to ordinary negative oxidation catalysts by means of which antioxidants normally exercise activity.

The higher the temperature to which the oil containing the spice residue is subjected, the greater the stabilizing action although the sharpest increase in stabilization is between about 325° F. and 450° F.

Example II

Bleached refined lard was prepared in the following manners:

Lard A.—Untreated.

Lard B.—1% of clove residue ground to about 50 mesh was dispersed therein, stirred for 5 minutes, and filtered.

Lard C.—1% of clove residue was dispersed therein, heated to 200° F. for 5 minutes, and filtered.

Lard D.—1% of clove residue was dispersed therein, heated to 300° F. for 5 minutes, and filtered.

Lard E.—1% of clove residue was dispersed therein, heated to 400° F. for 5 minutes, and filtered.

Lard F.—1% of clove residue was dispersed therein, heated to 450° F. for 5 minutes, and filtered.

The lards were then tested for stability as in Example I with the following results:

	Rancid after—
Lard A	1 hour
Lard B	2 hours
Lard C	2½ hours
Lard D	7½ hours
Lard E	23 hours
Lard F	26 hours

The heat treatments need not be prolonged, the enhanced antioxygenic effect being obtained in relatively short periods particularly where the higher temperatures are employed. Normally, the oil containing the spice residue may merely be heated to the desired temperature and allowed to cool, being held at the high temperature for a period of 10 minutes or more.

The heat treatment will usually be carried out at atmospheric pressure but the use of super or sub-atmospheric pressures may also be employed with satisfactory results.

This process may be utilized in the treatment and stabilization of a wide variety of refined or crude glyceride oils such as the vegetable oils and fats including cottonseed oil, corn oil, peanut oil, linseed oil, soya bean oil, olive oil, etc., the animal oils and fats including lard, tallow, oleo oil, cod liver oil, halibut liver oil, mackerel oil, menhaden oil, herring oil, shark liver oil, butter, etc., the glyceride soap oils and the sulfonated oils.

This invention is, however, particularly beneficial in the treatment of those glycerides which contain large proportions of unsaturated fatty acids, as the spice residue appears to react more completely with these unsaturated oils at the elevated temperatures.

The spice residues should be finely ground or crushed as, for example, placed in flour form. They may also be made into paste form by grinding with from 50% to 100% of an oil or by placing the combination through a colloid mill so as to disintegrate the cell structures and release the antioxygenic effect more readily at the higher temperatures.

The spice residues are usually charred in the oxidizable materials such as lard or fish oils, whereby the necessary interaction is obtained.

Although the spice residues may already have some antioxygenic effect when added to the glyceride oils and without the heat treatment, nevertheless such antioxidant power is limited and is much less than the stabilizing effect obtained after the addition of the spice residues and dispersion in the oil to be stabilized, followed by the heat treatment to over 250° F. and preferably to 325° F. to 450° F.

The stability of the treated oils will often be enhanced from 50% to 500% or more by the heat treatment in the presence of these substances as compared to the stability which would be obtained by the addition of the residues without the heat treatment described in this invention.

The most important features of the present invention reside in the fact that the added material is not normally present in the oil or oxidizable material to be stabilized and upon addition is thoroughly dispersed in such oil. The heat treatment is carried out for a sufficient length of time to increase the stability by usually not less than 50% over the stability of the unheated oil.

As a preferred method for the heating, the entire body of oil containing the spice residue thoroughly dispersed therein may be raised to the desired temperature with agitation, maintaining a uniform temperature throughout, and then permitted to remain at this temperature while agitating. The oil may then be allowed to cool without refrigeration.

While the spice residue is dispersed in the oil at the elevated temperature of about 400° F. superheated steam may, where desired, be continuously injected into the oil over a period as long as 4 to 6 hours and the objectionable flavors and odors originally present in the oil may be removed therefrom while the spice residue is exerting its enhanced antioxygenic effect.

It has been found particularly desirable for a small amount of spice residue to be added to high fat containing animal products, heating at atmospheric or elevated pressures to temperatures of about 250° F. so that the glyceride oil or fat contained therein is released from the meat or fish animal product and a highly stabilized animal glyceride is obtained.

For example, to a kettle of hog fat containing 70% total glycerides may be added 0.5% of clove residue against the weight of the hog fat and the combination placed in a steam kettle with steam being injected into the kettle to produce about 40 pounds pressure. After a 4 to 6 hour treatment, the pressure may be released and the rendered lard removed. The stability of the lard obtained in this manner will be much greater than if the clove residue had merely been added to the lard after rendering.

For example, when a small amount of a spice residue is added to hog fat and the hog fat containing the spice residue is then rendered at a temperature of 275° F. for 4 hours, the rendered lard removed from the rendering kettle has a far greater stability than where a proportionate

amount of the spice residue is added to the lard after rendering and the improvement in stability is even greater than where the spice residue is added to the lard after rendering and the lard containing the spice residue is then heated to 275° F. for 4 hours. Apparently a further interaction takes place by adding the spice residue to the rendering kettle where the rendering is conducted at over 250° F. resulting in a most highly stabilized oil.

In a similar manner, a small amount of spice residue may be added to the rendering kettles in the rendering of other meat and fish oils and fats including tallow, menhaden oil, herring oil, etc., or to the cooking kettles in the manufacture of fish meals, particularly high glyceride containing fish meals, and where the temperature is at least about 250° F., the desired interaction will result producing enhanced stabilization.

Where the glyceride oils are heated over long periods to temperatures over 250° F. and desirably to temperatures over 300° F., small amounts of the spice residues may be added to the oils at regular intervals of 5 to 20 hours followed by filtration to remove the insoluble portion before adding a fresh amount of the spice residue. In this manner, the glycerides will be held in highly stabilized and non-rancid condition over very long periods.

One of the highly unsaturated glyceride oils that has been found particularly desirable for treatment in accordance with the present invention is the crude unrefined corn oil obtained from the hydraulic or expeller expression of dry milled corn germ and where neither the corn nor the corn germ has been subjected to steeping in sulphurous acid water prior to removal of the germ.

There may be added to the crude corn oil a small proportion of the spice residue followed by elevated temperature treatment of at least about 250° F. and a highly stabilized glyceride oil product will be obtained.

It has been found most important to use the corn oil as expressed from the dry milled germ and which corn oil has not been subjected to any of the usual refining processes.

Although it is desirable to use clove and cinnamon residues which have been substantially exhausted of their oil content, other spice residues may be employed including the residues obtained following the removal of a substantial proportion of the oils and aromatic constituents from nutmeg, pepper, mustard, paprika, ginger, mace, caraway and other spice materials.

Together with or in lieu of the spice residues, there may also be employed their extracts and particularly those extracts obtained by the use of an alcohol soluble solvent. The extracts are desirably chosen from a solvent having the formula XOH where X is hydrogen or a low molecular weight aliphatic group. There may be particularly utilized methyl alcohol, ethyl alcohol, propyl alcohol or butyl alcohol.

The extracts may be prepared by immersing the finely divided residues in the solvent such as in methyl alcohol, using about from 5 to 15 parts of alcohol to each part of residue, agitating for from 5 minutes to 1 hour at a slightly elevated temperature, filtering out or otherwise removing the alcohol containing the dissolved extracted material, and then removing the alcohol, preferably under reduced pressure, whereby the ex-

tracted material remains substantially free of the solvent.

These extracts may be applied in the manner analogous to that described above for the residues themselves and will show an enhanced anti-oxygenic activity when added to oils followed by treating said oils at a temperature of at least 250° F. or more.

In addition to treating the glyceride oils and fats with the residues, the essential oils and particularly oxidizable unsaturated essential and perfume oils such as lemon oil and orange oil may similarly be treated with the spice residues followed by an elevated temperature treatment to enhance the antioxygenic effect.

The spice residues also exert an enhanced anti-oxygenic effect when added in small proportions to the substantially non-volatile, high molecular weight, hydrocarbon oils and particularly the lubricating oils followed by temperature treatments of over 250° F. and preferably between 350° F. and 500° F.

In carrying out the above described high temperature treatment, it is important that the solids of the spice residue be uniformly dispersed or distributed throughout the body of the oil in substantially fine particles and that the heating be carried out with substantial exclusion of the atmosphere or without contact with air.

It is moreover desirable for the spice residue to be maintained in dispersed condition during the heat treatment and so that the spice residue will not tend to settle or conglomerate or be present in the form of large lumps or particles since in the latter case the fully desirable results of the present invention are not obtained.

It is desirable that the oil after treatment in accordance with the present invention will not be materially changed in its odor or flavor. The oil will, however, have a darker color which may be removed by subjecting it to a bleaching operation.

The spice residues may where desired be subjected to boiling or treatment with acid such as by boiling clove residue in a 2% acetic acid solution for a period of from 20 minutes to 4 hours, followed by neutralization and drying and then utilized in accordance with the present invention.

The spice residues may also be first treated with saturated or superheated steam under pressure or under vacuum at temperatures substantially above 250° F., particularly in an acid medium having a pH of less than 6 and preferably less than 4.5. Such residues may then be utilized in accordance with the present invention.

It has also been found that desirable results are obtained where the finely divided spice residues are mixed with the oil or fibrous materials containing the glyceride oil and then the oil is heated to a temperature of, say, from 250° F. to 500° F. under a highly reduced pressure, such as under a gas pressure less than 1 pound per square inch to cause distillation of part or all of the glyceride oil composition and it has been observed that such distilled fraction is highly stable and is also free of the finely divided residue which has served as the stabilizing agent at the elevated temperature of distillation.

There may also be utilized in place of or together with the spice residues and included therewith various types of roots and particularly those used for making therapeutic or flavoring extracts, particularly after extraction with water, alcohol, ether or other solvents. For example, licorice, ginger, angelica, musk, gentian, bella-

donna, or ergot roots may be utilized for addition to oils followed by heating to over 250° F. in accordance with the present invention.

The present application is a continuation in part of application Serial No. 247,631 filed December 24, 1938.

Having described my invention, what I claim is:

1. A process of stabilizing oils subject to oxidative deterioration whereby they become less subject to such deterioration which comprises dispersing a small amount of a material selected from the group consisting of the finely divided spice residues and their alcohol soluble extracts in the oil and heating the oil to a temperature in excess of 250° F.
2. A process of stabilizing glyceride oils subject to oxidative deterioration whereby they become less subject to such deterioration which comprises dispersing a small amount of a material selected from the group consisting of the finely divided spice residues and their alcohol soluble extracts in the oil and heating the oil to a temperature in excess of 250° F.
3. A process of stabilizing substantially unsaturated glyceride oils subject to oxidative deterioration whereby they become less subject to such deterioration which comprises dispersing a small amount of a finely divided spice residue in the oil and heating the oil to an elevated temperature in excess of 250° F. while the oil is under sub-atmospheric pressure.
4. A process of stabilizing substantially unsaturated glyceride oils subject to oxidative deterioration whereby they become less subject to such deterioration which comprises dispersing a small amount of a finely divided spice residue in the oil and heating the oil to a sufficiently high temperature to char the residue while the oil is under sub-atmospheric pressure, and then filtering off the residue.

5. A stabilized oil normally subject to oxidative deterioration carrying the reaction product of a material selected from the group consisting of the finely divided spice residues and their alcohol soluble extracts in the oil, said reaction product having been formed by heating a small amount of the material in the oil to a temperature in excess of 250° F. whereby an enhanced stabilizing effect on the oil is obtained.

10 6. A stabilized glyceride oil normally subject to oxidative deterioration carrying the reaction product of a material selected from the group consisting of the finely divided spice residues and their alcohol soluble extracts in the oil, said reaction product having been formed by heating a small amount of the material in the oil to a temperature in excess of 250° F. whereby an enhanced stabilizing effect on the oil is obtained.

15 7. A glyceride oil normally subject to oxidative deterioration carrying the reaction product of a spice residue in the glyceride oil, said reaction product having been formed by heating a small amount of the spice residue in the oil to a temperature in excess of 250° F. whereby an enhanced stabilizing effect on the oil is obtained.

20 8. A glyceride oil normally subject to oxidative deterioration carrying the reaction product of a clove residue in the glyceride oil, said reaction product having been formed by heating a small amount of the clove residue in the oil to a temperature in excess of 250° F. whereby an enhanced stabilizing effect on the oil is obtained.

25 9. A glyceride oil normally subject to oxidative deterioration carrying the reaction product of a cinnamon residue in the glyceride oil, said reaction product having been formed by heating a small amount of the cinnamon residue in the oil to a temperature in excess of 250° F. whereby an enhanced stabilizing effect on the oil is obtained.

40

SIDNEY MUSHER.
